UNITED STATES PATENT OFFICE.

PASQUALE COLELLA, OF SWAMPSCOTT, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

BOOT OR SHOE AND METHOD OF MAKING SAME.

Application filed October 8, 1921. Serial No. 506,321.

This invention relates to boots and shoes and the process of making the same, and more particularly to a novel process of making a modified McKay type shoe and to the shoe produced by practising the process.

Heretofore in order to obtain a thin light edge and shank it has been customary to manufacture shoes by the turn process, but said shoes lack strength and long wearing

10 quality.

One object of the present invention is to produce a type of shoe which will provide wear from the full thickness of the outsole, as in a welt shoe, but which may have its 15 outsole fitted in such a manner as to give the shoe the appearance of a thin or feather edged turn shoe, an impossibility in welt shoe making, or with a different edge, as may be desired. Accordingly a feature of 20 the invention contemplates a mode of attachment of the outsole, in a McKay type shoe, whereby it is secured to the upper materials alone, throughout the forepart and shank, in combination with a flexible insole also 25 secured to the upper materials alone, whereby any edge appearance desired may be obtained by properly fitting the outsole and moulding it accordingly by direct pressure leveling.

30 Other objects of the invention are to produce a more flexible shoe than the McKay or Goodyear welt, which may be manufactured more cheaply and yet have a fine appearance, long wearing qualities, and extreme 35 comfort on the foot. These objects are accomplished by the elimination of lasting tacks; and consequently the full iron-bottom last; the use of a substitute mode of lasting which does not require the usual heavy 40 insole; the use of an extremely light insole so fitted as to cover the outsole stitching and leave a perfectly smooth interior tread surface; and the use of a long wearing outsole of good stock.

45 To the accomplishment of these objects and such others as may hereinafter appear, as will readily be understood by those skilled in the art, the invention comprises the features and combinations of parts, together 50 with the novel process of manufacture, hereinafter described and then particularly pointed out in the appended claims.

The preferred form of the invention is illustrated in the accompanying drawings in

which Figure 1 is a plan view of an insole, 55 for pointed toe shoes, fitted in the novel manner required for the present invention; Fig. 2 is a transverse section on the line 2—2, Fig. 1; Fig. 3 is a cross-sectional view of a partly completed shoe in which the novel 60 insole is embodied; Fig. 4 is a cross-sectional view of the same shoe at a later stage of its construction; Fig. 5 is a cross-sectional view of the completed shoe; and Fig. 6 is a cross-sectional view at the tip of the toe 65 of a completed shoe, having a pointed toe.

In the form of the invention illustrated in the drawings an insole blank 10 is slit at its edge to form two over-lying marginal lips 11 and 12. If the shoe to be manufactured 70 has a round toe, this edge slit is continuous from the breast line of one side to the breast line of the other. In the pointed toe style, however, it being difficult to stitch a pointed toe, the preferred construction of the new 75 insole is as is shown in Fig. 1, i. e. the edge slit is discontinuous and extends on each side from substantially the tip line to the breast line. At the ends of these slits are four marginal cuts 13, thus detaching said ends from the body of the insole and leaving the lips 80 connected to said body only along the base of the slit. In completing the fitting of the insole, the lips 11 and 12 are folded back upon opposite sides of the insole, as shown 85 more particularly in Fig. 3. While the insole blank originally is the full width of the bottom of the last, the turning back of these lips produces an insole which is narrower 90 than the bottom of the last throughout the length of the lips.

The insole 10 is now assembled upon the bottom of a last 14, as shown in Fig. 3, the shoe-maker positioning it by the heel and toe. An upper 15 is also assembled on the 95 last in the usual way, and is lasted in place by temporary lasting tacks (not shown). At this stage of the manufacture of the shoe the inlasted margin of the upper lies in contact with the under, infolded lips 11 of the 100 insole 10. The next operation is to secure the upper in place, and this is preferably accomplished by fastening the inlasted margin of the upper to the lips 11 by a line of fasteners such as the staples 16 applied by the Goodyear upper stapling machine (see Fig. 3). It will be understood that the upper heel seat is tacked as usual, and in the

case of a pointed toe shoe the upper is secured at the toe also by tacks. It will be observed that this method of lasting eliminates the full iron bottomed last used in 5 making McKay shoes.

After the upper has been secured in place, the bottom is filled with the usual cork filling 17 and an outsole 18, having the usual marginal channel 19, is applied to the bottom of the partly completed shoe and layed. The last 14 is then pulled and the outsole is McKay stitched, as at 20, to the upper, the horn of the stitcher contacting with the upper where it is left exposed by the infolded position of the upper insole lips 12 (see Fig. 4). To complete the shoe the insole lips 12, after being tempered in any convenient manner, are layed back over the McKay stitching as shown in Fig. 5. It will 10 be observed that both lines of securement lie within the edge of the insole. The outsole channel flaps 21 are layed and the shoe bottom is levelled, preferably by a direct pressure leveller, as is usual in McKay shoe-making.

As already mentioned, in manufacturing the style of shoes having a pointed toe the insole, forward of substantially the tip line, is not slit at its edge, and at this portion 20 of the shoe the upper is secured directly to the insole by lasting tacks 22 (Fig. 6), the outsole being secured to both the upper and insole by staples, or other metallic fasteners 23, but in other styles of shoes having 25 a round toe the McKay stitching may be continuous throughout the forepart and shank of the shoe.

In the manufacture of this shoe it is proposed to employ an extremely thin light insole blank 10 of not more than two irons in thickness. The edge slit is preferably centrally of the thickness of the insole, thus producing two over-lying lips 11 and 12 each of which is substantially one iron in thickness. In the manufacture of the shoe as described, the upper is secured to that one of these lips which lies on the under side of the insole, and the fasteners are of a kind that do not impair the flexibility of the shoe. It will be observed also that the McKay stitching extends only through the outsole and the margin of the upper so that, after the upper insole lip 12 has been layed, both the lines of fastenings in the completed 50 shoe are wholly below the insole. This leaves an absolutely smooth sock surface on which the foot of the wearer rests rendering this portion of the shoe the equal in comfort of a welt shoe.

60 The advantages of the novel shoe construction will be apparent to those skilled in the art. The light weight insole and absence of lasting tacks provides a very flexible shoe and the novel mode of securing the parts together also promotes flexibility. Further-

more no slip sole is required for covering the fastenings to provide a smooth sock surface since in the completed shoe the insole is the full width of the last bottom. As already referred to, the smooth sock surface is present as a result of the improved constructional features. By properly fitting the outsole the shoe may be given the appearance of a turn shoe and yet the weaknesses of the turn shoe are overcome i. e. 70 the present shoe has a more solid and permanent securement of the outsole, the outsole will give wear throughout its entire thickness, and the lining will fit and be un-wrinkled. While presenting the same appearance the present shoe is cheaper to manufacture than a turn since it does not require the high quality of stock that must be used to withstand the strain of turning. While the new shoe is of the McKay type a 80 saving is made in the insole stock and in the elimination of the full iron bottomed last.

The nature and scope of the invention having been indicated and the preferred 90 construction of the shoe and its process of manufacture having been specifically described, what is claimed as new, is:—

1. A boot or shoe comprising upper materials, an outsole; an insole having the full 95 width of the last bottom; and means securing the insole and outsole to the inlasted margin of the upper materials, but not to each other.

2. A boot or shoe comprising an insole 100 having upper and lower marginal lips; upper materials secured to one of said lips; and an outsole secured to the upper materials alone at a point opposite the other lip, whereby said other lip overlies said last 105 named line of securement in the finished shoe.

3. A boot or shoe comprising an insole having the full width of the last; an outsole; upper materials having their marginal portion interposed between the insole and outsole; and means within the edge of said insole for securing said materials to both the insole and outsole, said means for securing the insole to the upper lying between the 115 insole and outsole and said means for securing the outsole to the upper lying below the insole and unattached thereto.

4. A boot or shoe having an insole split 120 at its edge to form two lips, the under lip so formed being infolded and to which the inlasted margin of the upper materials is secured; an outsole; and fastenings securing the upper materials to the outsole beneath the upper lip formed by splitting the insole.

5. A boot or shoe having an insole provided with a marginal lip; upper materials contacting said lip; staple fastenings securing said materials to said lip; an outsole; stitching outside said staple fastenings 130

curing said materials to the outsole; and a second marginal lip on the insole overlying said stitching, but unattached to the upper materials.

5 6. An insole having its edge slit at each side from a point adjacent the tip line to a point adjacent the ball line at least, the two lips thus formed being folded back from the base of the slit on to the body of the insole 10 at opposite sides thereof.

7. An insole, too thin to be channeled successfully, having its edge slit centrally at each side adjacent the shank and ball at least, forming two overlying lips, and having 15 marginal slits through the insole at the ends of said lips thus detaching said ends from the body of the insole.

8. An insole substantially two irons in weight having its edge and margin so cut at 20 each side as to form two one iron lips at each side, attached to the insole at their bases only, extending approximately from the tip to the heel seat, said lips being turned and set on the opposite sides of the adjacent 25 stock of the insole body.

9. The method of making boots or shoes which includes the steps of assembling an insole and an upper on a last, the blank forming the insole being the full width of the 20 last; securing the inlasted margin of said upper to the insole along a line within its edge; applying an outsole; and securing the outsole to the upper alone beneath the margin of the insole.

35 10. The method of making boots or shoes which includes the steps of assembling an insole and an upper on a last; securing the inlasted margin of the upper to the insole by fastening means that do not project 40 through the upper side of the insole; applying an outsole; and securing the upper to the outsole leaving the margin of the insole outside of said fastening means unsecured to the outsole or the upper.

45 11. The method of making boots or shoes which includes the steps of assembling on a last an upper, and an insole having two lips at each margin, which together equal the entire thickness of the insole, previously

folded back upon opposite sides of the body 50 of the insole; securing the inlasted margin of the upper to the infolded insole lip against which it lies; applying an outsole; securing the outsole to the upper adjacent the line of securement of the upper to the 55 insole; and turning the infolded insole lips, inside the shoe, outward over the upper which lies outside the bases of said lips.

12. The method of making boots or shoes which includes fitting an insole with two 60 lips at each margin; folding both lips back upon opposite sides of the body of the insole; assembling said insole and an upper on a last; lasting the upper and stapling its inlasted margin to the infolded lip on the 65 under side of the insole; pulling the last; applying an outsole to the shot bottom; stitching the outsole to the upper outside the bases of the infolded lips; and laying the lip at the upper side of the insole over the 70 stitching.

13. As an article of manufacture, an insole having on one side a marginally extending lip for the attachment of a shoe upper and having the margin of the insole folded 75 back on itself on each side of the insole between substantially the tip line and the heel breast line of the insole.

14. A shoe comprising an upper, an insole having a channel lip to which the upper 80 is secured on its under side, an outsole attached to the shoe upper by through and through stitches which do not penetrate the insole and are covered by the margin of the insole on the interior of the shoe. 85

15. That improvement in methods of making shoes which consists in providing an inner sole with a flexible margin at the sides from the tip line to the breast line, folding said margin back to engage the sole 90 bottom, lasting and permanently securing the upper to the innersole, attaching the upper to the outsole only by a line of fastenings outside the fold of the innersole, and restoring the folded margin of the innersole 95 to its original position.

PASQUALE COLELLA.

- curing said materials to the outsole; and a second marginal lip on the insole overlying said stitching, but unattached to the upper materials.
6. An insole having its edge slit at each side from a point adjacent the tip line to a point adjacent the ball line at least, the two lips thus formed being folded back from the base of the slit on to the body of the insole at opposite sides thereof.
7. An insole, too thin to be channeled successfully, having its edge slit centrally at each side adjacent the shank and ball at least, forming two overlying lips, and having marginal slits through the insole at the ends of said lips thus detaching said ends from the body of the insole.
8. An insole substantially two irons in weight having its edge and margin so cut at each side as to form two one iron lips at each side, attached to the insole at their bases only, extending approximately from the tip to the heel seat, said lips being turned and set on the opposite sides of the adjacent stock of the insole body.
9. The method of making boots or shoes which includes the steps of assembling an insole and an upper on a last, the blank forming the insole being the full width of the last; securing the inlasted margin of said upper to the insole along a line within its edge; applying an outsole; and securing the outsole to the upper alone beneath the margin of the insole.
10. The method of making boots or shoes which includes the steps of assembling an insole and an upper on a last; securing the inlasted margin of the upper to the insole by fastening means that do not project through the upper side of the insole; applying an outsole; and securing the upper to the outsole leaving the margin of the insole outside of said fastening means unsecured to the outsole or the upper.
11. The method of making boots or shoes which includes the steps of assembling on a last an upper, and an insole having two lips at each margin, which together equal the entire thickness of the insole, previously folded back upon opposite sides of the body of the insole; securing the inlasted margin of the upper to the infolded insole lip against which it lies; applying an outsole; securing the outsole to the upper adjacent the line of securement of the upper to the insole; and turning the infolded insole lips, inside the shoe, outward over the upper which lies outside the bases of said lips.
12. The method of making boots or shoes which includes fitting an insole with two lips at each margin; folding both lips back upon opposite sides of the body of the insole; assembling said insole and an upper on a last; lasting the upper and stapling its inlasted margin to the infolded lip on the under side of the insole; pulling the last; applying an outsole to the shot bottom; stitching the outsole to the upper outside the bases of the infolded lips; and laying the lip at the upper side of the insole over the stitching.
13. As an article of manufacture, an insole having on one side a marginally extending lip for the attachment of a shoe upper and having the margin of the insole folded back on itself on each side of the insole between substantially the tip line and the heel breast line of the insole.
14. A shoe comprising an upper, an insole having a channel lip to which the upper is secured on its under side, an outsole attached to the shoe upper by through and through stitches which do not penetrate the insole and are covered by the margin of the insole on the interior of the shoe.
15. That improvement in methods of making shoes which consists in providing an inner sole with a flexible margin at the sides from the tip line to the breast line, folding said margin back to engage the sole bottom, lasting and permanently securing the upper to the innersole, attaching the upper to the outsole only by a line of fastenings outside the fold of the innersole, and restoring the folded margin of the innersole to its original position.

PASQUALE COLELLA.

Certificate of Correction.

It is hereby certified that in Letters Patent No. 1,595,453, granted August 10, 1926, upon the application of Pasquale Colella, of Swampscott, Massachusetts, for an improvement in "Boots or Shoes and Methods of Making Same," an error appears in the printed specification requiring correction as follows: Page 1, line 108, before the word "heel" insert the words *at the*; and that the said Letters Patent should be read with this correction therein that the same may conform to the record of the case in the Patent Office.

Signed and sealed this 14th day of December, A. D. 1926.
